THOMAS A. DE VILBISS, OF TOLEDO, OHIO, ASSIGNOR TO THE DE VILBISS MANUFACTURING COMPANY, OF TOLEDO, OHIO, A CORPORATION OF OHIO.

VALVE FOR ATOMIZERS OR THE LIKE.

1,097,008.

Specification of Letters Patent. Patented May 19, 1914.

Application filed January 15, 1913, Serial No. 742,126. Renewed April 6, 1914. Serial No. 830,084.

To all whom it may concern:

Be it known that I, THOMAS A. DE VILBISS, a citizen of the United States, and a resident of Toledo, in the county of Lucas and State of Ohio, have invented a certain new and useful Valve for Atomizers or the like; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates particularly to atomizers or similar instruments for the discharging of liquids in fine spray or vapor form; and has for its object the provision in an apparatus of this character, of simple 20 and improved means for opening or closing at will the communication of the liquid receptacle with both the air and the liquid discharge tubes and also with the atmosphere through the customary vent opening, 25 whereby when such means is in closed position the instrument can be inverted or placed in any position without danger of the liquid escaping therefrom, thus admirably adapting it for use by travelers, as it can 30 be packed without removing the liquid therefrom and without danger of the liquid leaking and soiling other articles packed therewith.

The invention is fully described in the 35 following specification, and while, in its broader aspect, it is capable of embodiment in numerous forms, a preferred embodiment thereof is illustrated in the accompanying drawings, in which—

40 Figure 1 is a top plan view of an apparatus embodying the invention with parts broken away and with the liquid receptacle removed. Fig. 2 is a central vertical section of the valve feature thereof on the line α in Fig. 1, and Fig. 3 is a section on the line y , y in Fig. 1, with the receptacle attached.

Referring to the drawings, 1 designates the liquid receptacle of an atomizer or other 45 spraying instrument, 2 the tube carrying head, which closes the neck thereof and is shown as being threaded into a ferrule part 3 attached to the receptacle neck, 4 and 5 the air and liquid discharge tubes, respectively, and 6 the nozzle with which the tubes

4 and 5 connect in any suitable manner, as is well understood in the art.

The head 2 has an axial bore or opening 7 therethrough, which is preferably outwardly tapered to enable a tapered plug-valve 8 to rotatably seat therein, as shown. The air-tube 4 or the passage thereof extends through the head 2 at one side of the opening 7, transversely thereof, and has a by-pass 9 into said opening, while the liquid-tube 5, in the present instance, projects radially from one side of the head 2 in the direction of projection of the air-tube and has the inner end of its passage extended through one side of the head and into the opening 7 thereof, as shown at 10. The air-tube has an extension 4' at one side of the head adapted for the attaching of the customary air-bulb tube thereto. The head 2 also has a passage 11 extending upward 75 from its lower end at one side of the opening 7 with its upper end preferably opening into the opening 7 immediately below the by-pass 9, but out of communication therewith except through the opening 7, as shown 80 in Fig. 3.

The valve 8 is held seated in the head 2 by threading a nut 12 on its lower end in abutment with the lower end of the head, or in any other suitable manner, and has a central passage 13 extending upward for a distance therein from its lower end and then angling transversely of the valve in position to register at its upper end with the passage 10 of the head when the valve is turned in 90 proper position therefor. A tube 14 is threaded or otherwise suitably secured at one end into the lower end of the valve passage 13 and projects therefrom down into the receptacle 1 to near its bottom. The 95 valve 8 also has a passage 15 therein, which, in the present instance, has its upper end opening without the center of the valve top to admit air at atmospheric pressure and has its lower end opening without a side of the 100 valve in position to register with both the by-pass 9 and upper end of the passage 11, as shown in Fig. 3, when the head and valve passages 10 and 13 are in register, thus enabling air to enter the receptacle from the 105 atmosphere through the passages 11 and 15 and also under pressure from the air-tube 4 through the passages 9, 15 and 11 when the instrument is being operated and the outer end of the passage 15 is closed, as by a thumb

of the operator, thereby causing what is known as a flooding or cleaning action.

The top portion of the valve 8 is enlarged to overlap the head 2, and is provided adjacent to one side thereof with a pin 16 which works in a registering groove 17 in the head to limit the relative turning movements of the head and valve, whereby the valve will stand in operative position 10 when at one limit of its movement and in inoperative position when at the other limit of its movement.

It is evident that I have provided a simple and efficient valve construction for atomizers 15 or the like whereby a placing of the valve in one position of its movement relative to the head will open communication both between the interior of the receptacle 1 and the liquid discharge tube 5 and between the 20 air-tube 4 and the interior of the receptacle, and also between the atmosphere and the interior of the receptacle, and a placing of the valve in another position of its movement will move the liquid and air passages of the 25 valve out of register with the respective liquid and air passages in the head to effectually prevent leakage from the receptacle should the instrument be inverted or placed on its side, thus adapting the instrument 30 for use by travelers or the like, as it can be packed with fine goods without removing the liquid contents from the instrument receptacle and without liability of such contents leaking from the receptacle to the injury of the goods with which it is packed.

I wish it understood that my invention is not limited to any specific construction or arrangement of the parts except in so far as such limitations are specified in the 40 claims.

Having thus described my invention, what I claim as new, and desire to secure by Letters Patent, is—

1. In an atomizer or the like, a receptacle, 45 a head carried by the receptacle and having a valve receiving opening therethrough and into the receptacle, said head also having air and liquid discharge passages therein in communication with said opening and having 50 an air passage opening communication between the interior of the receptacle and said head opening, and a valve mounted in

said head opening and having a passage which opens communication between the liquid passage of the head and the interior 55 of the receptacle and also having a passage which coöperates with said air passages to open communication between the air discharge passage and the interior of the receptacle when the valve is in one position of 60 its movement relative to the head, and a tube carried by the valve and extending down into the receptacle to form an extension of the liquid passage of the valve.

2. In an atomizer or the like, a receptacle, 65 a head carried thereby and having a valve receiving opening therein, said head also having an uninterrupted air discharge passage and an interrupted by-pass from said passage to the interior of the receptacle, 70 and a valve rotatably mounted in said opening and having a passage which when the valve is in one position of its movement opens communication between the atmosphere and said by-pass and also between the 75 air discharge passage and the interior of the receptacle through said by-pass.

3. In an atomizer or the like, a receptacle, a head carried by said receptacle and having a vertical opening therethrough with its inner end opening into the receptacle, said head also having air and liquid discharge passages and an interrupted by-pass from the air passage to the interior of the receptacle, a plug valve rotatably mounted in 85 said opening and having an extension down into the receptacle, said valve and extension having a passage therethrough for opening communication between the interior of the receptacle and said liquid passage when the 90 valve is in operative position, and said valve having a passage which opens to the atmosphere at one end and has communication at its other end with said interrupted by-pass to coöperate therewith to open communication with said receptacle from both the atmosphere and the air discharge passage.

In testimony whereof, I have hereunto signed my name to this specification in the presence of two subscribing witnesses.

THOMAS A. DE VILBISS.
